(57) **CLAIM**

The ornamental design for a battery charger, as shown and described.

DESCRIPTION

FIG. 1 is a front elevation view of all embodiments of a battery charger showing our new design.

FIG. 2 is a top plan view of the first embodiment of the battery charger.

FIG. 3 is a right elevation view of the first embodiment of the battery charger, the left elevation view being a mirror image thereof.

FIG. 4 is a rear elevation view of the first embodiment of the battery charger.

FIG. 5 is a right elevation view of the second embodiment of the battery charger, the left elevation view being a mirror image thereof.

FIG. 6 is a top plan view of the second embodiment of the battery charger.

FIG. 7 is a rear elevation view of the second embodiment of the battery charger.

FIG. 8 is a right elevation view of the third embodiment of the battery charger, the left elevation view being a mirror image thereof.

FIG. 9 is a top plan view of the third embodiment of the battery charger; and,

FIG. 10 is a rear elevation view of the third embodiment of the battery charger.

The broken lines are for embodiment purposes only and form no part of the claimed design.
